UNITED STATES PATENT OFFICE.

JAMES CLAYTON, OF COVENTRY, ENGLAND, ASSIGNEE TO COURTAULDS, LIMITED, OF LONDON, ENGLAND.

THREAD-GUIDE FOR ARTIFICIAL-SILK MACHINES.

1,224,070.

Specification of Letters Patent. Patented Apr. 24, 1917.

Application filed April 18, 1916. Serial No. 91,988.

To all whom it may concern:

Be it known that I, JAMES CLAYTON, a subject of the King of Great Britain, residing at 12 Middleborough road, Coventry, 5 England, have invented new and useful Improvements in Connection with Thread-Guides for Artificial-Silk Machines, of which the following is a specification.

This invention has for its object to provide means whereby the funnels, or thread-guides, used in machines for the manufacture of artificial silk, to guide the thread into the rotating spinning boxes, can be put in place in correct position with great facility which is a matter of considerable importance as these funnels, or thread-guides, are made of glass and it is therefore impossible to produce them all of the same length and size generally, and moreover they are liable to be out of the straight line. The said funnels, or thread-guides, as hitherto arranged in the machine have been supported by the enlargement, or cup, at their upper end and this has necessitated skilled and careful work in fitting the funnels, or thread-guides in place or has resulted in the lower ends of the funnels, or thread-guides, being frequently out of center with the spinning boxes and sometimes too high, or too low, relatively to the interior of the spinning boxes, to give equal and satisfactory results.

According to this invention the funnels, or thread-guides, are furnished with a ferrule, or sleeve, which surrounds that part of the 35 said funnel, or thread-guide, which is to be supported through the medium of the ferrule, or sleeve, in the fitting, or bearing, of the machine. The said ferrule, or sleeve, is affixed to the funnel, or thread-guide, while 40 it is held between two supports one above, and the other below, the upper one, for instance, engaging the upper end of the orifice of the tubular part of the funnel, or thread-guide, and the lower one engaging the lower end of the said orifice. The ferrule, or sleeve, is supported so that its longitudinal axis is in the same line as that in which the axial lines or centers, of the aforesaid upper and lower supports are situated. 45 The means by which the funnel, or thread-guide, and the ferrule, or sleeve, can be supported may be of any suitable kind which will comply with these requirements, but it is preferred to employ a device constructed 50 as hereinafter described with reference to

the accompanying drawing, this device being the subject of my divisional application Serial No. 115,528, filed August 17, 1916.

When the funnel, or thread-guide, and the ferrule, or sleeve, are supported as aforesaid, a substance which can by heat, or otherwise, be brought to a condition such that it is pourable, and will set sufficiently (such as pitch for example) is poured into the space between the ferrule, or sleeve, and when this has set the ferrule, or sleeve, will be secured to the funnel, or thread-guide, in such a position, in common with all the funnels, or thread-guides, similarly made, that when a funnel, or thread-guide has to be renewed, this can be readily done without special adjustment by a skilled workman. The upper end of the ferrule, or sleeve, is preferably formed with an outwardly projecting flange which, when the ferrule, or sleeve, is being applied to the funnel, or thread-guide, will rest against the top of the arm around the hole in which the ferrule, or sleeve, is supported while it is being applied, and which flange, when the funnel, or thread-guide, is in the machine, will similarly rest against the top of the support for the said funnel, or thread-guide, in the said machine.

I will describe, with reference to the accompanying drawing, how this invention can be performed, but I do not limit myself to the precise details illustrated in this drawing and described with reference thereto.

Figure 1 shows a funnel, or thread-guide, in accordance with this invention. Fig. 2 is a sectional elevation and Fig. 3 is a transverse section, (on the line A, B, Fig. 2) of the device which I prefer to use in carrying out this invention, showing a funnel, or thread-guide provided with a ferrule, or sleeve, supported therein.

1, is tubular part of the funnel, or thread-guide, and 2, is the enlargement, or cup part, at top. The ferrule, or sleeve, which is applied in accordance with this invention, is marked 3.

The aforesaid device for carrying out this invention consists of an upright 4, formed, at top, with a projecting arm 5, and at bottom with a projecting arm 6. The lower arm 6, carries a cone-ended bearing piece 7, and the upper arm carries a cone-ended bearing piece constituted by the rod 8, capable of sliding in the upper arm 5, the 105

- 5 said rod being provided with a knob 8^a for convenience of manipulation and being fixable in position by a set-screw 9. The arm which carries the ferrule, or sleeve 3, to be fixed to the funnel, or thread-guide, is marked 10, and is shown as being made in two parts connected together by a hinge pin 10^a, and formed with an opening to receive and fit the said ferrule, or sleeve, one 10 portion of which opening is in the fixed part of the arm, the other portion of the said opening being in the part of the arm which can be turned upon the hinge-pin 10^a. When the funnel, or thread-guide, and ferrule, or sleeve, are in place the movable part of the arm 10, is turned against the fixed part and the two parts are secured together by a screw, or clip. In the drawing a wire 15 clip 11, is shown for this purpose.
- 20 20 When the parts are thus secured pitch, or other suitable substance, is introduced to the space between the inside of the ferrule, or sleeve, 3, and the outside of the tubular part of the funnel, or thread-guide, as shown at 12, a rubber-band, or some material such as putty, for example, being applied to the lower part of the space to retain the pitch till it is set.
- 25 What I claim is—
- 30 1. A thread guide for use in machines for the manufacture of artificial silk, said guide comprising a tubular member and a supporting ferrule mounted thereon at a predetermined distance from its lower end.

2. In a machine for the manufacture of 35 artificial silk, a plurality of thread guides comprising tubular members, and a supporting ferrule mounted on each at a predetermined, uniform distance from the lower ends of said guides.

3. A thread guide for use in machines for the manufacture of artificial silk, said guide comprising a tubular member and a supporting ferrule mounted thereon at a predetermined distance from its lower end and 40 having its axis precisely alined with that of the tubular guide.

4. A thread guide for use in machines for the manufacture of artificial silk, said guide comprising a tubular member and a supporting ferrule mounted thereon at a predetermined distance from its lower end and 45 having an outstanding supporting flange.

5. A thread guide for use in machines for the manufacture of artificial silk, said guide comprising a tubular member and a supporting ferrule mounted thereon at a predetermined distance from its lower end and 50 having an outstanding supporting flange at its upper end.

In testimony whereof I have signed my name to this specification in the presence of two subscribing witnesses.

JAMES CLAYTON.
